UNITED STATES PATENT OFFICE.

CARLOS VILLEGAS, OF BROOKLYN, NEW YORK.

CALCULATOR FOR MATURITIES.

1,384,789.

Specification of Letters Patent. Patented July 19, 1921.

Application filed May 1, 1919. Serial No. 294,106.

To all whom it may concern:

Be it known that I, CARLOS VILLEGAS, a citizen of Costa Rica, and a resident of the borough of Brooklyn, county of Kings, city 5 and State of New York, have invented certain new and useful Improvements in Calculators for Maturities, of which the following is a description.

My invention relates to the calculation of 10 the dates of maturity of drafts and the like which have to pass through the mail, and has as its principal object the provision of means whereby such dates may be determined both accurately and rapidly.

15 The novel features of my invention are pointed out with particularity in the appended claims. The invention itself, however, together with further objects and advantages, will best be understood by reference to the following description taken in connection with the accompanying drawing, in which—

20 Figure 1 is a plan view, partly broken away, of apparatus for carrying out my invention as arranged for use;

25 Fig. 2 is a plan view of the bottom one of the two sheets shown in Fig. 1;

Fig. 3 is a section taken on the line $y-y$ of Fig. 1.

30 In the separate views, the same part is designated by the same reference character.

As indicated in Fig. 1, in my complete device I employ a top sheet or cover 1, beneath which a sheet, such as 2, is used in 35 order to obtain the date of maturity of a given instrument.

The sheet 2 as shown is one of a set of twelve synoptic tables, there being one for each month of the year whereas I provide 40 only one cover sheet, such as 1. Each sheet, such as 2, has marked off thereon a large rectangular space 105, the bottom edge of which is indicated at 3, the right edge at 4, the left-hand edge at 5, and the top edge at 45 6. This large rectangle is divided by parallel lines into rectangles such as 110 of intermediate size, as for instance, the one bounded by lines 7, 8, 9 and 10. Consequently the rectangles 110 of intermediate size are 50 arranged in vertical columns and horizontal rows. Each vertical column of rectangles 110 is labeled, and the dates of maturity of instruments of the same tenor are arranged in a given column, marked "Sight," "3 55 days," etc., as the case may be. Each horizontal row of rectangles 110 contains the

maturity dates of instruments which require a given number of days in the mail to reach the places on which they are drawn. The days in the mail, one way, of all the rows, 60 appear in the column marked "Mail" at the left of the large rectangle 105, the dates being so arranged that maturities, of all instruments requiring the same number of days in the mail appear in the same row. 65

Each of the intermediate rectangles 110 is divided in turn into smaller rectangles, one of which is indicated at 111, there being space enough in the intermediate rectangles for thirty-six of these small rectangles. The 70 dates appearing in the small rectangles 111, are preferably arranged in six columns, the first five columns from the left containing five dates, and the sixth column containing three, four, five or six, depending upon the 75 number of days in the month for which the particular sheet or table is made up. The dates in the small columns just mentioned are arranged so that the one occurring first is in the upper left hand corner of the intermediate rectangle 110, the dates in each such small column being one day later as the column is followed from top to bottom, and the date at the top of one column being one day later than that at the bottom of 80 the column to its left. The sheet or table shown in Fig. 2 is made up for the month of April and the small rectangles containing the individual dates in the intermediate rectangle 110 at the upper left-hand corner of 85 the large rectangle are numbered from "1" to "30," the numbers increasing in the manner previously described for the dates. This intermediate rectangle, having the small rectangles numbered, preferably contains the 90 dates of maturity of those instruments first to mature, these being instruments payable at sight and drawn on places requiring the minimum time in the mail to reach. 95

Accordingly it will be seen that the sheet 100 for April, as shown in Fig. 2, has the date "5.1" in the upper left-hand corner of the upper left-hand intermediate rectangle, this being the date on which a sight-draft, dated April first, would become due if drawn on 105 a place fifteen days away by mail one way, or thirty days away both ways. The date of maturity of any other sight draft dated in April, requiring the same number of days in the mail, would be found in the same 110 group of dates, or, in other words, in the same intermediate rectangle in the small rec-

tangle corresponding to the date of the instrument. Similarly, the date of maturity of a sight draft dated April first and drawn on a place requiring twenty days in the mail 5 one way, for a letter to reach it, is found in the second group or intermediate rectangle at the upper left-hand corner of this group, this date being May eleventh. Similarly, the date of maturity of a sight draft drawn 10 on the same place and dated April nineteenth is found in the small space or rectangle in the second group in the "sight" column, which has a position corresponding to the one marked "19" in the first group in 15 this column. In a similar way the date of maturity may be found for any instrument having a tenor and time in mail given in the chart. The chart shown in Fig. 2 is constructed to include instruments of a tenor 20 up to one hundred and fifty days and ninety-five days in the mail for tenors and mail time commonly used in computing maturities. The dates at the lower right-hand corner of the sheet run into the succeeding 25 year, these dates being shown on Fig. 2 by inclined numerals as indicated at 112.

It will be seen that if the order of the dates in the groups is known, there is no necessity of numbering the spaces containing 30 the individual dates, but I find that numbering the spaces reduces the liability to errors. However, for reasons that will presently appear, I prefer to number the small rectangles only in the first intermediate rectangle 110 35 in the "sight" column as indicated at 113, and there being thirty days in April these numbers run from "1" to "30", increasing in the same order as explained for the dates in the groups.

40 In order to facilitate obtaining the desired date of maturity and to insure against error, I prefer to use a cover sheet, such as 1, and I provide for use in connection with said cover sheet at least two, and preferably four 45 rectangles, such as 114, of the same size as intermediate rectangles 110, near the corners and outside of the large rectangle 105. Said two or four rectangles 114 are divided into small rectangles of the same size as 111, 50 and these small rectangles are numbered from "1" up in the same manner as previously described in connection with the numbers 113. However, the figures in rectangles 114 are placed in the centers of their spaces 55 and the cover sheet 1 has apertures such as 12 cut therein and so arranged that when a given number, such as "7" in rectangles 114 appears in the apertures in the cover sheet, then the dates in the corresponding positions in all the intermediate rectangles 110 60 are brought into view. Consequently, the dates of maturity of all instruments drawn on the seventh of April can be read quickly and accurately. To facilitate the use of 65 cover sheet 1, it is ruled into intermediate

rectangles in the same way as sheet 2, the rectangles in which the openings for the present date are placed being marked A, B, C and D respectively. The cover sheet can, however, be omitted while still using the 70 broad principle of my invention.

While the arrangement of the dates of each group in six columns as described above is the arrangement preferred by me, I consider as within the scope of my invention 75 any device in which dates are arranged in groups and the groups arranged in columns and rows according to the tenor and time in the mail of the instruments, and in which the dates have the same arrangement in the 80 groups.

Having thus described my invention, I claim:

1. A means for obtaining dates of maturity, comprising a table for a given month 85 having the maturity dates arranged in groups, said groups being arranged in intersecting columns and rows according to the tenor and time in the mail of the instrument, the order and arrangement of the dates 90 being the same in all groups.

2. A means for obtaining dates of maturity, comprising a table for a given month having the maturity dates arranged in groups, said groups being arranged in intersecting columns and rows according to the tenor and time in the mail of the instrument. 95 the order and arrangement of the dates being the same in all groups, each of said groups having as many individual dates 100 therein as there are days in the said given month.

3. A means for obtaining dates of maturity, comprising a table for a given month 105 having the maturity dates arranged in groups, said groups being arranged in intersecting columns and rows according to the tenor and time in the mail of the instrument, the order and arrangement of the dates being the same in all groups, each of 110 said groups having as many individual dates therein as there are days in the said given month, the individual dates in each group being arranged in order of occurrence in six smaller columns, there being five dates in 115 the first five of such smaller columns counting from left to right, and as many in the sixth of such smaller columns as are necessary to make up the number of days of the given month, the first date in a group to occur being at the upper left-hand corner, and the last at the lower right-hand corner thereof.

4. A means for obtaining dates of maturity, comprising a sheet for a given month 125 having the maturity dates arranged in groups, said groups being arranged in intersecting columns and rows according to the tenor and time in the mail of the instrument, the arrangement of the dates being the same 130

- in all groups, each of said groups having as many individual dates therein as there are days in the said given month, the individual dates in each group being arranged in order 5 of occurrence in six smaller columns, there being five dates in the first five of such smaller columns counting from left to right, and as many in the sixth of such smaller columns as are necessary to make up the 10 number of days of the given month, the first date in a group to occur being at the upper left-hand corner, and the last at the lower right-hand corner thereof, said sheet having at least two groups of figures in addition 15 to said groups of dates and beginning with "1" running up to the number of the last day of said given month, said groups of figures being arranged in the same order as said groups of dates, and a cover having 20 apertures therein so spaced that when two of said apertures are placed over a given number in said groups of figures the correspondingly placed date in each group of dates will be visible.
- 25 5. A means for obtaining dates of maturity, comprising a sheet for a given month having the maturity dates arranged in groups, said groups being arranged in intersecting columns and rows according to the 30 tenor and time in the mail of the instru-

ment, the order and arrangement of the dates being the same in all groups, each of said groups having as many individual dates therein as there are days in the said given month, and a cover having apertures therein 35 so spaced that when two of said apertures are placed over the correspondingly placed dates in two of said groups the corresponding dates in the remainder of said groups may be read therethrough.

6. A means for obtaining dates of maturity, comprising a sheet for a given month having the maturity dates arranged in groups, said groups being arranged in intersecting columns and rows according to 40 the tenor and time in the mail of the instrument, the order and arrangement of the dates being the same in all groups, each of said groups having as many individual dates therein as there are days in the said given month, a cover having apertures therein so spaced that when two of said apertures are placed over the correspondingly placed dates in two of said groups the corresponding 45 dates in the remainder of said groups may be read therethrough, and means for indicating to the operator the proper relative position of the cover with respect to said sheet corresponding to the instant date.

CARLOS VILLEGRAS.
